HAND-BAG

Application filed October 28, 1930. Serial No. 491,658.

Our present invention relates generally to hand-bags and the frames therefor, and has particular reference to inverted-frame constructions.

5 A general object of our invention is to provide a handbag of improved structural characteristics, and of extremely attractive and unique outward appearance.

In Reissue Patent No. 17,514, granted to us December 3, 1929, we show a bag of the inverted frame type in which a pair of frame members are provided with outwardly disposed channels so that the fabric can be passed over the outer walls of and into these 15 channels. These frame members are shown as symmetrical and as symmetrically associated so that the handbag fabric conceals the frame almost in its entirety.

One of the main features of our present invention lies in providing a bag structure which retains many of the desirable features of a bag of the foregoing character, and which, at the same time, provides for less than a total concealment of the frame in a unique 25 and novel manner. More particularly, it is a feature of our invention to construct the frame members in such a way that a predetermined and particular portion of the frame remains constantly exposed to view.

30 A more particular feature of our invention lies in providing a construction wherein the inner wall of one of the channeled frame members is exposed in a particular manner.

Another feature of our invention resides 35 in a novel association, with a bag of the foregoing character, of locking means in the form of a pair of cooperable latch elements. The particular and novel construction of frame members in accordance with our invention 40 cooperates in a particular manner with the novel type of locking means which we have provided.

Another general object of our invention is 45 to provide an improved structure of the character referred to wherein the advantageous features of resilience, so far as the locking means is concerned, are efficiently retained without mitigating the advantageous features of our present construction.

50 We achieve the foregoing objects, and such

other objects as may hereinafter appear or be pointed out, in the manner illustratively exemplified in the accompanying drawing, wherein—

Figure 1 is an elevational view of a handbag frame constructed in accordance with our invention, portions being broken away for the sake of clearness; 55

Figure 2 is an end elevation of the same, showing in dot and dash lines the manner in 60 which the frame members move when the bag is opened;

Figure 3 is a fragmentary plan view of the frame;

Figure 4 is an enlarged cross-sectional view 65 taken substantially along the line 4—4 of Figure 1; and

Figure 5 is a perspective view of a complete bag.

We have illustrated our invention as applied to a frame designed for a handbag having an inner compartment as well as an outer compartment, but it will be understood that the frame portion which forms the inner compartment has been included in the disclosure 75 only for the purpose of illustrating a typical bag in which the invention may be employed.

The outer portion of the frame is formed of two U-shaped members 10 and 11 which are hinged to each other at the free ends of 80 the legs of the U, as by means of the pivot pins 12 and 13. The inner frame portion is similarly composed of two U-shaped members designated generally by the reference numeral 14, and also hinged to each other at the free ends of the legs of the U, the pins 12 and 13 being sufficiently long to serve this purpose also.

Each of the frame members 10 and 11 is 85 substantially U-shaped in cross-section, as shown most clearly in Figure 4, and, thus, each frame member may be said to be channeled inwardly to provide spaced inner and outer walls which extend upwardly and outwardly. The inner channeling of the frame member 10 provides the inner and outer upstanding spaced walls 15 and 16, respectively. The frame member 11 embodies the inner and outer upstanding spaced walls 17 and 18, respectively. When the bag is closed, the 90 95 100

inner walls 15 and 17 lie adjacent to one another. Each of the frame members 10 and 11 is preferably, though not necessarily, in the form of a metal stamping.

In accordance with our present invention, it is to be noted that the arms or legs of the frame member 10 are shorter than those of the frame member 11. Upon referring to Figure 4, it will be seen that when the bag is closed, only the upper edge of the inner wall 15 contacts with, and overlies, the inner wall 17. This leaves the major portion of the outer surface of the inner wall 17 exposed to view when the bag is closed. It will be observed that only the midportion of this inner wall is unconcealed, the arms or legs of the frame member 11 being completely concealed when the bag is closed, in the customary manner.

This construction is of particular and unique importance in view of the completed bag structure. More particularly, upon referring to Figure 4, it will be noted that the handbag fabric extends, as at 19, upwardly over the outer wall 18 and thence into a secured position within the channel between the walls 17 and 18. This causes a complete concealment of the outer wall 18 at all times. Similarly, it is to be noted that the fabric passes upwardly, as at 20, over the outer wall 16 and thence into secured position within the channel between the walls 15 and 16. This conceals not only the outer wall 16 at all times, but also the inner surface of the wall 15. It is to be particularly observed that a portion or ridge of handbag fabric 21 extends upwardly beyond the upper edge of the wall 16, and that a similar ridge or doubled-back portion of fabric 22 extends upwardly beyond the upper edge of the wall 18.

The importance of this construction will be more clearly observed in Figure 5, wherein it is to be noted that the bag, though completely closed, presents to view the outer surface of the inner wall 17, attractively framed within a margin of the handbag fabric. For example, in Figure 5, it is to be noted that the visible and exposed portion 17 is presented against a background 22 at its upper edge, composed of handbag fabric, and it is framed at its lower edge by the ridge of handbag fabric 21. Also, at the sides, where the wall 17 extends downwardly into normally concealed position, it is to be noted that the handbag fabric extending over the wall 18 provides a ridge or marginal portion which serves as a framework for the exposed wall 17.

The latching means which we have provided consists, preferably, of a pair of yieldably interengageable latch elements, each of which is mounted on one of the walls of one of the frame members. We have shown a latch element 23 in the form of a globular body attached to the midportion of the upper edge of the wall 17, and we have shown a

complementary and similar globular body 24 attached to the midportion of the upper edge of the wall 15. Because of the offset nature of the construction, we have mounted the element 24 upon a shank 25 which is preferably 70 of flattened and attractive ornamental metal or the like.

For the purposes of symmetry, it is desirable that the bodies 23 and 24 lie exactly on opposite sides of the center line of the 75 bag. This means that the supports for these elements will be slightly offset with respect to such center line. In accordance with our invention, the shank portion 25 is constructed as to lie symmetrically across the center line, 80 despite the fact that the latch element 24 is offset from the center line. Thus, in Figures 1 and 5, it will be clearly observed that the lateral edges 26 and 27 of the shank 25 lie at equal distances from the center line 85 of the bag on opposite sides thereof.

The bag is preferably, though not necessarily, provided with a handle or strap 28, which may be attached to rings or the like 90 29 and 30 mounted upon the frame member 11. Also, the interengagement between the elements 23 and 24 is preferably, though not necessarily, effected by means of a finger or projection 31 carried eccentrically by the element 24 and adapted to engage in a camming manner with the curved adjacent surface of the element 23. When the bag is opened and closed, the finger 31 wedges its way past the element 23, and the resilience which such an action necessitates is provided 100 by the peculiarly efficient capability of the upstanding walls upon which the elements 23 and 24 are mounted.

The exposed surface 17 and the outer surface of the shank 25 provide a symmetrical 105 ornamentation for the bag which has been hitherto impossible of achievement in bags of the inverted-frame type, wherein the main objective has always been to conceal completely the metallic frame portion of the bag 110 structure. Not only is a portion of the frame exposed, but it is to be noted that the exposed surface is peculiarly positioned, being not on the exterior of the bag, but at the midportion thereof.

Thus, upon viewing Figure 4, it will be observed that the outer surface of the wall 17, which is exposed to view when the bag is closed, lies almost exactly midway between the outer surfaces of the walls of handbag 115 fabric 19 and 20. As a result, the wall 17 affords a convenient and efficient place for the application of delicate ornamentation, engraving, enameling, or the like. It is, after a fashion, protected by its positional relationship with respect to the fabric and the bag as a whole, and, accordingly, it is not subjected to the wear and abrasion which an exposed ornamented surface might be susceptible to if otherwise positioned.

Furthermore, the superposition of the portion 25 over the midportion of the exposed wall affords another highly efficient and attractive place for delicate ornamentation. 5 For example, the wall 25 might be ornamented in a contrasting manner with respect to the exposed wall 17.

In general, it will be obvious that we have provided a bag structure of peculiarly efficient and attractive character, retaining all 10 the advantageous characteristics, mode of operation, and general appearance of the extremely popular inverted-frame bag, while at the same time providing for a predetermined exposure of certain frame portions 15 in novel relationship to the bag as a whole.

It will be obvious that changes in the details herein described and illustrated for the purpose of explaining the nature of our 20 invention may be made by those skilled in the art without departing from the spirit and scope of the invention as expressed in the appended claims. It is therefore intended that these details be interpreted as illustrative, and not in a limiting sense.

Having thus described our invention and illustrated its use, what we claim as new and desire to secure by Letters Patent is—

1. In a handbag, a pair of U-shaped members hinged to each other at their ends, each member being channeled inwardly to provide spaced inner and outer walls extending outwardly, whereby the margin of the handbag fabric can be passed over the outer walls to conceal the latter and into secured position within said channels, the arms of one frame member being shorter than those of the other so as to provide one of the members with an exposed wall, and a pair of interengageable 30 latch elements, one of which is mounted on one of the walls of the longer frame member and the other of which is mounted on the inner walls of the shorter frame member, the last-named latch element being provided 35 with an ornamental shank arranged centrally with respect to the frame members and adapted to overlie the center of said exposed wall when the bag is closed.

2. In a handbag, a pair of U-shaped metal 40 frame members hinged to each other at their ends, each member being channeled inwardly to provide spaced inner and outer walls extending outwardly, whereby the margin of the handbag fabric can be passed over the outer walls to conceal the latter and into secured position within said channels, and the legs of one frame member being shorter than those of the other, whereby the inner metallic wall of said other member remains exposed when the bag is closed, so as to enhance 45 the ornamental character of the bag, and permit of the ornamental treatment of said exposed surface.

3. In a handbag, a pair of U-shaped frame 50 members hinged to each other at their ends,

each member being channeled inwardly to provide spaced inner and outer walls extending outwardly, whereby the margin of the handbag fabric can be passed over the outer walls to conceal the latter and into secured position within said channels, the arms of one frame member being shorter than those of the other, and a pair of latching members one of which extends upwardly beyond the top of the inner wall of the frame member having the larger arms and the other of which extends upwardly beyond the top of the shorter frame member a greater distance than the other so as to bring the two latching members into coactive engagement, 70 when the handbag is closed.

4. In a handbag, a pair of U-shaped frame members hinged to each other at their ends, each member being channeled inwardly to provide spaced inner and outer walls extending outwardly, whereby the margin of the handbag fabric can be passed over the outer walls to conceal the latter and into secured position within said channels, the arms of one frame member being shorter than those of the other, and a latch comprising a pair of globular camming elements carried by the midportions of said frame members, respectively and extending upwardly from their respective frame members to different extents 85 so as to bring the globular elements into registration, the element mounted on the shorter frame member being provided with a flattened shank adapted to overlie the exposed wall of the other frame member when the 90 bag is closed.

In witness whereof we have signed this specification this 27th day of October, 1930.

CHARLES J. McCABE.
